STOVE

Filed Oct. 31, 1928

INVENTOR
Leon Wygodsky
BY
William W. Varney
ATTORNEY

UNITED STATES PATENT OFFICE

LEON WYGODSKY, OF BALTIMORE, MARYLAND

STOVE

Application filed October 31, 1928. Serial No. 316,117.

The object of my invention is the providing of a compact, portable stove adapted for the utilization of fuel substances.

A further object of my invention is the providing in a single element means for support upon which the stove may stand and means for support to rest an article to be heated with a container for containing the fuel, all in a folded condition being in compact form.

10 A further object of my invention is the provision of means for controlling the burning of the fuel and its protection when not burning, and also for extinguishing the flame when desired.

15 With the foregoing and other objects in view, my invention consists of the novel construction, combination and arrangement of parts as hereinafter specifically described and illustrated in the accompanying drawings, wherein is shown the preferred embodiment of my invention, but it is understood that changes, variations and modifications may be resorted to which come within the scope of the claims hereunto appended.

20 25 In the drawings of the hereinafter described embodiment of my invention, Figure 1 shows a plan view of my stove with the control cover closed in position for transportation covering the fuel within the receptacle provided for it; Fig. 2 is a view in elevation, partially in section, of the apparatus shown in Fig. 1, with the cover open, however, and the various supporting means bent into operative position; it is, in fact, a view taken

30 35 through 2—2, of Fig. 1, after the supporting means has been bent into operative position and the cover opened for lighting the fuel; Fig. 3 is a sectional view taken through 3—3 of Fig. 1.

40 45 Similar numerals refer to similar parts throughout the several views.

1 is the main body provided with flange 2 and a receptacle, or cup, 3. 4 are the legs, or supporting members, which are stamped out of the body and provided for supporting the stove upon a table, stand or upon whatever it might be placed. Normally, the legs are flush with the main body 1, and in use are bent downwardly and outwardly towards

50 the flange 2, to form a support, as shown in

Fig. 2. 5 are supporting members stamped out of the legs and adapted to be bent upward or in the opposite direction to legs 4 for supporting a vessel to be heated. Normally, these supports 5 are in the position as shown 55 in Figs. 1 and 3, that is, almost but not quite in the plane of the main body 1, being raised sufficiently to permit a combined damper and cover, or slide, 6 to pass between the end of the supporting member 5 and the main body 60 65 1 for its support or maintenance. These supporting members and legs 4 and 5 are preferably ribbed or beaded to give rigidity for their length, as shown especially in Fig. 3 in order that when they are bent bending at their base or juncture with the body will be insured.

Damper, or slide, 6 is hinged or pivoted to main body 1 at 7, and is provided with handle or catch 8. Normally, this cover or slide is 70 in position as shown in Fig. 1, covering the fuel in depression or cup 3, but may be pulled out by means of handle 8 so that the fuel may be lighted. 9 is a guide stamped from the main body 1 and under which cover 6 operates 75 and is guided. 10 is a member stamped out of the main body 1 and may be bent upward, forming a support substantially of the same length when in upward or bent position as supporting members 5, the purpose of this 80 member 10 being to support a curling iron, or other body, which would not conveniently rest upon a three-point support. It will be noticed that the legs 4 have their free ends curved or concaved so that when they are bent down into operative position there will be point contact with the supporting table to reduce conduction of heat from the hot stove to the supporting table; the shape of the legs further helps to radiate the heat before the same reaches the point of contact. Furthermore, the circulation of the air through the opening in the plate and legs after the legs have been bent into the working position 85 helps to cool the stove and to collect and direct the heat picked up by the circulating air back into the flame or under the cooking utensil.

This stove is intended primarily for convenient burning of solid fuel in the shape of 100

tablets, but also semi-solid, or even liquid fuel, can be used.

The operation of my invention is as follows:

5 The cup or receptacle 3 is supplied with some well known fuel substance, and when the device is not in use the cover or damper plate 6 is slid over the fuel as shown in Figure 1, the downturned end of the handle 8 engaging the flange 2 and serving as a stop. When 10 it is desired to use the stove, legs 4 are bent downward and the supporting members 5 are bent upward. The slide is pulled back, uncovering the cup, the fuel is ignited, and anything 15 to be heated is placed upon the supports 5 so as to be supported over the stove. The burning of the fuel is controlled by cover or slide 6, which may be closed over, or partially over, the cup as the degree of combustion 20 may be required, and entirely over the cup if total extinction of the flame is desired. The cover or slide acts as a damper and may therefore be so termed. Furthermore when the slide or damper is in its extended position 25 it serves as a handle for lifting the stove about or otherwise handling it.

From the drawings and descriptions, it will be noticed that the stove is stamped out of a substantially single piece to form the main body, cup, legs, upper supporting member and flange, the only moving part being the cover, or slide. This stove is intended primarily as a portable heater where simplicity and rapidity are required.

Having thus described my invention, what I claim and desire to secure by Letters Patent is:

1. A stove comprising, a receptacle, an extended edge around said receptacle, a flange at the periphery of said edge, stampings within said edge to bend downwardly to form legs and stampings within said edge to bend upwardly to form supports, said two stampings being one inside the other.

40 2. A stove comprising, a receptacle, an extended edge around said receptacle, a flange at the periphery of said edge, stampings within said edge to bend downwardly to form legs, stampings within said edge to bend upwardly to form supports, a damper operatively mounted on said edge, and a guide stamped from said edge for said damper.

45 3. A stove comprising a body member of sheet metal formed with a depressed portion serving as a cup for containing fuel, said body being formed with a plurality of stamped out portions arranged about the depressed portion, certain of said stamped out portions being bendable downwardly to constitute legs and others being bendable upwardly to extend above the body and serve as supports, said second named stamped out portions lying within the confines of the first named stamped out portions.

60 4. A stove comprising a body member of

sheet metal formed with a depressed portion serving as a cup for containing fuel, said body being formed with a plurality of stamped out portions arranged about the depressed portion, certain of said stamped out portions being bendable downwardly to constitute legs and others being bendable upwardly to extend above the body and serve as supports, and a damper plate pivoted near the outer edge of the body and swingable to cover or uncover said depressed portion to a selected extent for controlling the combustion of fuel. 70

5. A stove comprising a body member of sheet metal formed with a depressed portion serving as a cup for containing fuel, said body being formed with a plurality of stamped out portions arranged about the depressed portion, certain of said stamped out portions being bendable downwardly to constitute legs and others being bendable upwardly to extend above the body and serve as supports, and a damper plate pivoted near the outer edge of the body and swingable to cover or uncover said depressed portion to a selected extent for controlling the combustion of fuel, said damper plate serving as a handle when in said uncovering position and having a downturned end engageable with the edge of the body to serve as a stop. 80

6. A stove comprising a body member of sheet metal formed with a depressed portion serving as a cup for containing fuel, said body being formed with a plurality of stamped out portions arranged about the depressed portion, certain of said stamped out portions being bendable downwardly to constitute legs and others being bendable upwardly to extend above the body and serve as supports, and a damper plate pivoted near the outer edge of the body and swingable to cover or uncover said depressed portion to a selected extent for controlling the combustion of fuel, said damper plate serving as a handle when in said uncovering position and having a downturned end engageable with the edge of the body to serve as a stop, said downturned end serving as a finger catch to facilitate initial movement of the damper plate to uncovering position. 90

7. A stove comprising a body member of sheet metal formed with a depressed portion serving as a cup for containing fuel, said body being formed with a plurality of stamped out portions arranged about the depressed portion, certain of said stamped out portions being bendable downwardly to constitute legs and others being bendable upwardly to extend above the body and serve as supports, and a damper plate pivoted upon the body and movable to cover or uncover said depressed portion to a desired extent, said second named stamped out portions normally lying in a plane spaced from the body. 100

to permit the damper plate to be received between them and the body.

8. A collapsible stove comprising a circular disk of sheet metal having a peripheral flange and formed centrally with a depressed portion constituting a cup for containing fuel, the body being formed with a circumferentially arranged series of stamped out portions joined to the body near the outer edge and having their inner ends free, said stamped out portions being bendable downwardly and outwardly to serve as supporting legs, said stamped out portions having other stamped out portions within the confines thereof with their inner ends free and adapted to be bent upwardly to constitute supports, a damper plate pivoted upon the body near the outer edge thereof and swingable to cover or uncover the fuel to a selected extent, said damper plate being normally received between the body and the second named stamped out portions.
